TICKET ISSUING MACHINES

Alfred Johnson Pearson, Swanley, England, assignor to
British Transport Commission, London, England

Filed Jan. 11, 1960, Ser. No. 1,531

Claims priority, application Great Britain Jan. 19, 1959
5 Claims. (Cl. 101—66)

This invention relates to ticket issuing machines suitable for use by ticket issuing personnel such as the conductors of omnibuses, trolley buses and tramcars, which machines are usually portable and are carried by the operator, so that they must be as light and as simple as possible.

In such machines there is provided a printing drum having on its periphery an arcuate plate bearing raised characters for printing certain information which is required on all the tickets issued, and having openings therein to accommodate discs bearing on their peripheries other characters for printing changeable information such as the price of the ticket, the number of the stage at which the vehicle was boarded by the passenger, and the class of ticket (ordinary, return, child, etc.). The discs are rotatable in the drum by suitable setting means.

To provide information regarding the tickets sold, it is desirable to record the variable information printed on each ticket, and the object of the present invention is to enable this information to be printed, on a record strip retained in the machine, by the ticket printing drum.

According to the present invention, in a ticket issuing machine including a printing drum against which a ticket strip is pressed by a pressure roller so that tickets are printed by rotation of the drum, said drum bearing characters providing fixed information required on all tickets issued and variable information required to be printed on the tickets being provided by characters on the peripheries of discs rotatably mounted in the drum and grouped together so that the variable information is confined to one part of the ticket, the printing surfaces of the characters on said discs stand proud of the printing surfaces of the characters on the printing drum, and a record strip is passed over a second pressure roller arranged to press the said record strip only against the characters which stand proud so that only those characters are reproduced on the record strip.

The discs bearing the characters providing the variable information are preferably mounted co-axially to rotate about an axis parallel to the axis of the printing drum.

The periphery of the printing drum may be bulged outwardly at the position of the rotatable discs.

A take-up roller may be provided for the record strip and may be rotated by means operated by the rotation of the printing drum.

The invention is hereinafter described with reference to the accompanying drawings in which:

FIGURE 1 is a front elevation of a ticket issuing machine embodying the invention with part of the casing removed;

FIGURE 2 is a section on the line 2—2 of FIGURE 1 showing some of the parts separated from the machine;

FIGURE 3 is a section in a plane parallel to that of FIGURE 2, through the printing drum and the record strip carrying assembly;

FIGURE 4 is a rear view of the record strip carrying assembly;

FIGURE 5 is an underneath view of the record strip carrying assembly; and

FIGURE 6 is a sectional plan on the line 6—6 of FIGURE 2, showing a detail.

Referring to FIGURE 1 of the drawings the ticket

2

issuing machine comprises two compartments arranged side by side, the compartment 10 housing the ticket printing mechanism and the compartment 11 housing totalising mechanism providing an indication of the total number of tickets sold and their cash value.

10 A printing drum 12 rotatably mounted in the compartment 10 has fixed to its periphery an arcuate printing plate 13 bearing, in relief, characters (letters and/or figures) providing fixed information to be reproduced on all tickets printed, the printing plate 13 being cut away to form a window 14 extending across the width of the drum. A row of settable discs 15, 16, 17, 18, 19 and 20 are mounted in the drum for rotation about a common axis eccentric to the drum axis, the discs having formed in relief on their peripheral surfaces characters for providing variable information on the tickets printed. A row of characters on these discs at their radially outermost points with respect to the drum axis lies across the centre of the window 14, these characters standing slightly proud of the characters on the printing plate itself, and the edges of the plate at the window are bulged slightly outwardly radially of the drum, as shown in FIGURES 2 and 3, so as to have substantially the same radial distance from the drum centre as the surfaces of the characters in that row.

20 In the machine illustrated, the discs 15 and 16 bear digits providing the number of the fare stage from which the ticket is available, the disc 17 bears letters indicating the class of ticket, the discs 18 and 19 bears fractions and digits respectively indicating pence, and the disc 20 bears digits indicating shillings, so that these last three discs together show the ticket value.

25 The printing drum 12 is rotatable by means of an external handle 21.

30 The mechanism for setting the discs forms no part of this invention, and is not described herein, mechanisms for this purpose being well known. The shillings disc 20 is set by rotation of a quadrant 22 on the outer side of the compartment 11, the pence and half-pence discs 19 and 18 are set by a wheel 23 mounted between the quadrant 22 and the side of the compartment 11, and the discs 15, 16 and 17 are set by knobs 24 and 25 coaxial with the boss of the handle 21, the knob 24 setting the discs 15, 16 and the knob 25 setting the disc 17.

40 45 Tickets are printed on a paper strip 26 (FIGURE 2) carried on a spool in the upper part of the compartment 10 and led between the surface of the printing drum 12 and the surface of a pressure roller 27 which is resiliently urged against the surface of the printing drum, rotation of the printing drum feeding the paper strip forwardly and ejecting it through a slot in the machine so that each ticket, after printing, can be torn off and handed to the passenger for whom it is issued. An inking roller 28 for the printing drum is mounted below and behind the said drum.

50 55 As shown in FIGURES 2, 3, 4 and 5, a frame 29 is mounted in the compartment 10 behind the printing drum 12, the frame 29 consisting of two side plates 31, 31 spaced apart by spacing tubes 32, 32 against the ends of which the plates 31 are held by screws 33. Between the side plates 31 there is mounted, on a spindle 34, a roller 35 of rubber or like material, and a second spindle 36, parallel to the spindle 34, carries a second roller 37 of rubber or like material, preferably formed with longitudinal ribs. The spindle 36 also carries a star wheel 38 and a collar 38a having flats on its periphery with which a spring arm 38b co-operates to position the spindle 36 after each increment of movement. The plates 31 are cut away at their lower rearward portions, and a pair of resilient plates 39 secured at their forward parts to the plates 31 in front of the cut-away portions of the latter,

are cranked inwardly as shown in FIGURE 5 to grip the ends of a roll of paper strip 40 carried by a spindle 41 engaged in slots 42 extending inwardly from the rear edges of the resilient plates 39. A second pair of slots 43 extending inwardly from the rear edges of the plates 31 accommodate the spindle 44 of a take-up roller 45, the paper strip 40 being led from the roll on the spindle 41 over the roller 35 and on to the take-up roller 45. Springs 46 coiled about screws 47 mounted in the plates 31 and anchored to the screws 33 securing the plates 31 to one of the spacing tubes 32 bear against the spindle 44 to press the take-up roller 45 towards the roller 37, so that the latter roller bears on the surface of the paper strip wound on the take-up roller and, when rotated, rotates the take-up roller to wind the paper strip on to it.

The frame 29 is located in the compartment 10 by engagement of the ends of the spindle 34 in notches 48 in locating blocks 49 (FIGURE 2) secured to the walls of the compartment 10, and is so positioned that the paper strip, where it passes over the roller 35, is at a radial distance from the centre of the printing drum such that it is not engaged by the characters on the printing plate as the drum rotates, but is engaged by the characters on the discs 15 to 20 inclusive. The locating blocks 49 are secured each by a single screw 50, as shown in FIGURE 2, and are adjustable about the said screws to provide the correct spacing of the roller 35 from the printing drum axis by means of adjustable abutments 50a. A striker 51 is mounted on one side of the printing drum 12 in such a position that during rotation of the said drum, after the discs 15 to 20 have passed the roller 35, it engages the star wheel 38 and rotates it through one step. The rotation of the printing drum as the discs 15 to 20 pass the roller 35 advances the strip 40 through a short distance, leaving the strip slack between the said roller 35 and the take-up roller, the subsequent rotation of the star wheel 38 winding the slack on to the take-up roller 45 and drawing a small further length of the strip off the roll on the spindle 41, to provide a space between successive imprints on the strip.

The frame 29 is urged inwardly by blade springs 52 mounted on a removable back-plate 53 closing an opening in the back of the compartment 10, and is located against tilting about the spindle 34 by engagement of one end of the spindle 36 in a third locating block 54 secured to the wall of the compartment 10.

The back-plate 53, as shown in FIGURE 3, has an upward projection 55 at its upper end to engage the inner face of a fixed part of the rear wall of the compartment 10, and is shaped adjacent its lower end to provide an inwardly projecting U-shaped bend forming a transverse channel 56. The back-plate 53 is held in place in the machine by a rod 57 passing through the channel 56 and through holes in the side plates of the compartment 10, the rod 57 being enlarged in diameter at one end and the enlargement being grooved circumferentially at 58 (FIGURE 6) to receive a locking member 59 mounted by means of a blade spring 61 in the inner face of the back-plate. The blade spring 61 urges the locking member 59 into the groove 58, but can be released by passing any suitable rod-like member through a hole 62 in the back-plate 53 and displacing the locking member. A pocket 63 is provided on the inner side of the back-plate to receive a puncturable sheet covering the hole, so that, by providing code-markings on the sheet, an indication is given as to whether any unauthorized removal of the back-plate has taken place.

It will be seen that, at each operation of the machine to print and deliver a ticket, the information set up on the discs 15 to 20 will be printed on the record strip 40, and a length of the record strip slightly greater than that occupied by the line of print, but very much shorter than a complete ticket, will be transferred to the take-up roller

45. Thus a record strip 40 of relatively short length is produced which bears sufficient information to enable the ticket sales to be analysed in considerable detail, since not only the fares paid but also the passenger density at all points along the route can be ascertained.

The record strip, when filled, is removed by removing the back-plate 53, taking out the frame 29, disengaging the springs 46 from the spindle 44, and removing the spindle and take-up roller by sliding the former along the slots 43. A fresh record strip 40, rolled on the spindle 41, is then inserted between the resilient plates 39, passed over the roller 35 and its end secured to the take-up roller 45, for example by an adhesive. The resilient plates, besides holding the roller on the spindle 41 in place, provide a braking action to prevent the strip from being unrolled too freely.

It will be understood that the information provided on the settable discs may be modified as desired, and that the number of discs may be greater or less than six. Moreover, the disc setting means may be of any suitable type.

I claim:

1. A ticket issuing machine comprising a rotatable printing drum, means for rotating said drum, a pressure roller in surface contact with the printing drum, means resiliently urging said pressure roller into contact with the drum, said drum having characters provided on its periphery and providing fixed information required on all tickets issued, a spool containing a paper ticket strip disposed adjacent the drum with the ticket strip passing between the nip of the drum and the pressure roller and being fed by the rotation of the drum so that the ticket strip moves with the drum during passage of the characters past the pressure roller, a plurality of discs mounted on the drum and being selectively rotatable and having characters on their peripheries, the characters radially projecting beyond the periphery of the drum and providing variable information, roller means disposed adjacent the drum, means containing a paper record strip disposed adjacent the drum with the record strip passing between the drum and the roller means and being urged by the roller means only against the characters on the discs so that these characters are reproduced on the record strip and the record strip passing between the characters on the discs and the roller means when the drum is rotated and being moved only when the discs are passing in contact with the roller means.

2. A ticket issuing machine according to claim 1, wherein the discs bearing the characters providing the variable information are mounted co-axially to rotate about an axis parallel to the axis of the printing drum.

3. A ticket issuing machine according to claim 1, wherein a take-up roller is provided for the record strip, means operated by the rotation of the printing drum being provided for rotating the said take-up roller.

4. A ticket issuing machine according to claim 3, wherein rotation of the take-up roller is effected by mechanism including a star wheel driven by a projection on the printing drum.

5. A ticket issuing machine according to claim 3, wherein the take-up roller is rotated by a friction roller engaging the part of the record strip wound on to the said take-up roller.
